GOVERNING MECHANISM FOR WATER-DRIVEN TURBINES.

1,180,583.

Specification of Letters Patent.

Patented Apr. 25, 1916.

Application filed July 14, 1915. Serial No. 39,847.

To all whom it may concern:

Be it known that I, ANTON GAGG, a citizen of the Republic of Switzerland, residing at Zurich, Switzerland, have invented new and 5 useful Improvements in or Relating to Governing Mechanism for Water-Driven Turbines and other Prime Movers; and I do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

This invention relates to means for securing freedom from oscillation in governing mechanism for prime movers and more particularly water-driven turbines by the use 20 of hydraulic, indirectly-acting speed governors.

The essential features of the present invention consist in providing means whereby the travel of the controlling organ of the 25 auxiliary motor participates only within relatively narrow limits of the movements of the centrifugal governor. A yielding member, for instance a dash-pot, is so connected with a controlling linkage that the 30 centrifugal governor is capable of continuing its travel after the controlling organ has reached its end positions. The centrifugal governor, immediately upon a reversing of its movement, imparts to the controlling 35 organ the same degree of movement.

A constructional embodiment of the invention consists in providing, in connection with the dash pot, springs that act to return the dash pot cylinder after each displacement to its mid position, for the purpose of 40 restoring after each governing the position of the controlling organ in dependence upon the centrifugal governor, said position being required for keeping a certain speed or 45 number of revolutions of the prime mover.

The apparatus is adapted for use both in connection with constant speed governing systems and systems of the kind wherein a certain given new speed or number of revolutions corresponds to each new load.

The accompanying drawings illustrate constructional examples of mechanism embodying the invention adapted for use in connection with water-driven turbines, and 55 also illustrate diagrammatically the gov-

erning operations or effects obtainable by means of the governing mechanism according to the present invention.

Figure 1 is a front elevation, partly in section of one form of construction. Fig. 2 60 is a vertical section of the casing of the controlling valve, showing the governing piston arranged within the casing in its lowest position. Fig. 3 is a vertical section of the casing of the dash-pot, showing the piston of 65 the latter displaced relatively to the middle of the dash pot casing. Fig. 4 is a vertical section corresponding to Fig. 2 showing the governing piston in its uppermost position. Fig. 5 illustrates diagrammatically 70 the governing operations or effects obtainable by means of the mechanism shown in Figs. 1 to 4. Fig. 6 is a vertical section of a second constructional form. Fig. 7 is a vertical central section of the dash pot shown in 75 Fig. 6, illustrating the parts in another position. Fig. 8 illustrates diagrammatically the governing operations or effects obtainable by means of the mechanism shown in Figs. 6 and 7. Fig. 9 is a vertical section 80 of a third constructional form. Fig. 10 illustrates diagrammatically the governing operations or effects obtainable with positive and negative returning arrangements 85 respectively. Fig. 11 is a vertical section of a dash-pot, illustrating springs arranged externally to the dash-pot cylinder. Fig. 12 is a vertical section of a friction coupling that may be used instead of a dash pot. Fig. 13 is a horizontal section at line A—B of 90 Fig. 12.

In the example shown in Fig. 1 the casing 2 of the controlling valve for the auxiliary motor which can work with a fluid under pressure for instance water or oil under 95 pressure has stops, by which the travel of the governing piston 3 movable within the casing 2 is kept within narrow limits. In the present case the auxiliary motor comprises the casing 4 and differential pistons 5, 5^a and is connected to a pipe system 30, that receives water under pressure from the main supply pipe 31 leading to the water turbine 32, that drives also the centrifugal governor 1. A dash pot is intercalated in 100 the linkage system between the governing piston 3 and the centrifugal governor 1. The dash pot consists essentially of a cylinder 6 and a piston 7. The spaces in the dash pot cylinder 6 above and below such piston 110

are filled with oil and the dash piston is formed with a small perforation 11 that places the said spaces in communication with each other. Upon the centrifugal governor 1 being caused to rotate at a higher speed owing to the load on the prime mover being lightened its sleeve raises the left hand end of the lever 8 and turns such lever in a clockwise direction about its stationary fulcrum 9. The right hand end of the lever 8, acting through the link 10 thereupon presses the dash pot piston 7 downward. The perforation 11 is however so small in diameter, that in the short period of the movement, which is momentarily in a downward direction it is not possible for a sufficient quantity of oil to flow from the lower to the upper side of the piston 7 to admit of the piston moving freely relatively to the cylinder 6. A momentary driving connection, although of a slightly elastic or yielding nature, is accordingly set up between the piston 7 and the cylinder 6, and consequently the piston 3 of the controlling valve to which the cylinder is rigidly connected, will also be pressed downward into the position shown in Fig. 2. In this position of the controlling piston 3 the way is clear to the outlet pipe 12 for the water under pressure on the right hand side of the large piston 5 of the auxiliary motor, so that the pressure on the right hand side of the piston 5 falls. The continuously prevailing high pressure of the water between the large piston 5 and the small piston 5^a is consequently able to push the two pistons to the right and thus by means of the link 14 and lever 15 to turn the main governor shaft 16 in a counter-clockwise direction, this resulting in a closing movement of the main admission valve 33 or equivalent devices of the prime mover. A slight upward movement of the sleeve of the centrifugal governor 1 will suffice to push the piston 3 of the controlling valve far enough downward to cause such piston to travel the entire length of its stroke, as such travel is quite small relatively to the whole travel of the governor sleeve. It need for instance only amount to one millimeter out of the mid-position. The right hand end of the lever 8 is however capable of traveling altogether through a distance that is much greater than the aforesaid travel of the piston 3. Even when the controlling piston 3 is seated at the bottom in the casing 2, see Fig. 2, the speed governor is still capable of further movement in the original direction, as the dash pot piston 7 then becomes displaced downward to a corresponding extent within the dash pot cylinder 6 and displaces the oil below it up through the perforation 11, the said piston moving into the position shown in Fig. 3. When however the speed of the centrifugal governor decreases after the main inlet

valves or equivalent devices have been moved into the position corresponding to the new load, so that the governor sleeve begins to descend, the dash pot piston 7 which at this time is being drawn upward by the right hand end of the lever 8 again becomes momentarily coupled, by means of the oil over such piston, to the dash pot cylinder 6, the piston at this time being in the position shown in Fig. 3, it having been moved downward out of its mid position. The piston 7 as it is being drawn upward draws upward along with it the dash pot cylinder 6 and consequently the piston 3 of the controlling valve, until the latter piston reaches its mid position, a fresh period of repose being thereby set up. This governing operation is graphically represented in Fig. 5 wherein the time corresponding to any given governing operation is indicated as abscissæ measured from left to right, the ordinates representing on the one hand the speed or number of revolutions n of the prime mover (the thin line) and on the other hand the amount of opening O of the main inlet valves or the like (the heavy line). At the point of time t^1 suppose the preexisting state or repose to be interrupted by a lightening of the load on the water-driven turbine. As a result the turbine speed will be accelerated and the centrifugal governor 1 raises its sleeves and acts as hereinbefore described, through the dash pot 6-7, distributing valve 2-3, and auxiliary motor 4-5-5^a, to turn the governing shaft 16 in a counter clockwise direction and thus close the main distributing valves or the like.

Referring to the diagram, Fig. 5, the speed of the prime mover is represented as having had the value n^1 during the first state or period of repose, that is to say, up to the time t^1 and the main inlet valves or the like were open by an amount O^1 . Up to the time t^2 , the speed of the prime mover rises to the amount n^2 , while at the same time the centrifugal governor acts in accordance with the governing operation hereinbefore described to bring about a reduction of the sectional area of opening of the admission valves or the like down to the amount O^2 . At the same t^2 the amount of energy transmitted by the water on the turbine shaft is exactly equal to the duty required of the turbine at the increased speed n^2 . The auxiliary motor 4, 5, 5^a however moves further in a direction to close the main admission valves thereby causing the speed of rotation to fall from the value n^2 . This in turn causes the governor sleeve to descend and thus raise the dash pot piston 7. As already stated the dash pot piston 7 draws the dash pot cylinder 6 and consequently the piston 3 of the controlling valve upward, that is to say, draws the piston 3 into its mid posi-

tion. The closing movement of the main admission valves or the like is momentarily interrupted. Now it is to be understood that the travel of the controlling valve is intended to be very small as compared with that of the rod 10 or the sleeve of the centrifugal governor 1, for instance only as 5 1 to 20. In this case a fall in the speed of rotation of 1/20th of the amount of the degree of nonuniformity of the spring governor (amounting say, to 4 %,) that is to say, a fall of only about 1/5th % of the speed n^2 , will suffice to bring about the return of the controlling piston 3 to its mid position as 10 hereinbefore described.

As indicated in Fig. 5 the speed falls from the value n^2 only by the very small amount between that point and n^3 where a 15 fresh state of repose is set up and at which point the main admission valves or the like 20 are open by the amount O^3 . Now if the device constituting the invention had not been employed the speed would have fallen to the value n^1 and beyond. The closing movement of the admission valves would have 25 continued for a correspondingly long period, that is to say, up to the time t^4 , at which point the amount of admission of the prime mover would have already become far too 30 small, with the result that a permanent oscillation or hunting action would be set up in a well-known manner, as indicated by the dot and dash lines in Fig. 5.

In the fresh state of repose before referred 35 to at the point t^3 , the dash pot piston 7 occupies relatively to its cylinder 6 the position shown in Fig. 3 in which it is displaced in a downward direction and which is accordingly not identical with the mid position 40 shown in Fig. 1. Moreover the new speed n^3 will in general be by such an amount higher than the original speed n^1 as would not be admissible for instance for 45 driving electric generating machines. It is however possible to restore the original speed n^1 for the new state of repose if the dash pot be constructed as shown in Fig. 6 and substituted for the simple dash pot 50 shown in Fig. 1. In this construction it is only in its middle portion that the bore or internal diameter of the dash pot cylinder 17 is made sufficiently small to correspond exactly to the dash pot piston 18. Above 55 and below this portion the internal diameter of the cylinder 17 is greater. Bearing against the shoulders thus formed are freely fitting rings 19 and 20 loaded by springs 21 and 22. Now upon the piston 18 being forced downward out of its mid position by 60 the centrifugal governor owing to a reduction in the load on the water driven turbine, it will force the ring 20 downward and accordingly compress the lower spring 22, see Fig. 7. The upper spring 21 remains in 65 its previous position as its supporting ring

19 rests against the shoulder formed by the constructed part of the casing 17. Owing to the one-sided or unbalanced action of the spring 22 the piston 18 is no longer in equilibrium relatively to the cylinder 17 and the 70 spring 22 tends to force the piston back relatively to the cylinder 17 into the mutual mid position shown in Fig. 6. A mutual action will now take place in governing mechanism fitted with a dash pot constructed in 75 this manner, between the centrifugal governor 1, dash pot 17 to 22 and controlling valve 2, 3, until with the turbine under the new load, both the controlling valve 2, 3, the dash pot 17 to 22 and the speed governor 80 1 have returned to their original positions and the water-driven turbine has thereby been caused to run at its original speed. In this way the turbine will be seen to have been provided with means for governing at 85 constant speed. The action of the arrangement is illustrated graphically in Fig. 8. Up to the time t^4 the initial state of repose or "dwell" has lasted with a certain load. The speed during this period amounted to 90 n^4 and the main admission valves or the like of the turbine were opened by the amount O^4 .

After the reduction in load the speed of the turbine rises to the amount n^5 and then falls to the amount n^6 . Up to this point the 95 action is identical with that already described with reference to Fig. 5 up to the time t^3 . Now however the action of the compressed spring 22 comes into play. The dash pot cylinder 17 and along with it the 100 controlling piston 3 are pushed downward slightly by the action of this spring and only slowly or just at such a speed as allowed by the small perforation in the dash pot piston 18, thus allowing the auxiliary motor to continue its closing movement. As a result the speed falls from the amount n^6 (Fig. 8), which corresponds to the amount n^3 in Fig. 5, still further and the controlling piston 3 105 is returned to its mid position owing to the falling of the governor sleeve caused thereby. Let this state of things be supposed to have been attained at the time t^4 . The main admission valves are then open by the amount O^7 which is somewhat less than the 110 amount corresponding to the new load at the normal speed. The speed has momentarily the value n^7 and owing to the slightly too small amount of opening of the main admission valves is constantly falling. This 115 would at once again bring about an opening movement were it not for the fact that the dash pot cylinder 17 together with the controlling piston 3 is further displaced relatively to the dash pot piston 18 in the direction of closing under the action of the spring 22. By properly proportioning the size of the perforation in the dash pot piston 18 it is possible to insure that the upward movement of the piston 18 caused by 120 125 130

the falling of the sleeve of the spring governor and the downward movement of the dash pot cylinder relatively to the dash piston will neutralize each other, so that the controlling piston 3 will remain in its mid position until the ring 20 again bears on the shoulder formed by the portion of the dash pot cylinder 18 of reduced diameter and the one sided action of the spring 22 ceases to exist. At this moment the continued falling of the speed causes the main admission valves of the water driven turbine to be again opened, to an extent O^s corresponding to the new load, with the result that at the time t^s the new state of repose or "dwell" is attained. As in this new state of repose the dash pot piston 18 again occupies the same position relatively to the dash pot cylinder 17 as at the time t^s before the beginning of the governing operation, the position of the governor sleeve will also be the same, and the speed n^s after the close of the governing operation will be equal to the speed n^s before the latter.

Fig. 9 shows how it is possible, as compared with the simpler governing mechanism illustrated in Fig. 1, to arrange between the auxiliary motor, or in effect the main governing shaft 16, and the lever 8 of the centrifugal governor, instead of the dash pot 6, 7 shown in Fig. 1, not only the dash pot shown in Figs. 6 and 7 fitted with returning springs, but in addition thereto a returning linkage system of a construction which in itself is known. This arrangement has for its object to establish a certain relation of dependence, necessary for certain power-supply services, between the load on one hand and the speed on the other. For the sake of simplicity in Fig. 9 all parts that are similar in the arrangements shown in Fig. 1 and Fig. 6 respectively are denoted by the same numbers as already used in those figures. In the arrangement shown in Fig. 9 the pivotal axis 9 of the governor lever 8 is no longer stationary or fixed, as in Fig. 1, but is carried on the returning linkage system 24 to 28. By means of this linkage system the point 9 is displaced at each movement of the main governing shaft 16, such displacement being either in an upward or downward direction for a movement of the shaft 16 in one and the same direction, for instance a clockwise direction, according as the link 27 is connected on the left hand or right hand side of the central plane of the double bent lever 26. The lasting displacement or "dwell" of the point 9 during a governing operation has the effect of compelling the sleeve of the spring governor 1 to assume a different position in order to set up a new state of repose, with the result that a lasting alteration on the speed obtains in the case of the new load. Now the difference in the speed between

given amounts of load will be greater or lesser according as the point of attachment of the link 27 to the horizontal arm of the double lever 26 is at a greater or less distance from the pivotal point 23 of such lever. In the full line-position of the link 27 the point 9 will be raised in connection with a closing movement of the main governing shaft 16 and consequently the sleeve of the spring governor 1 must occupy a higher position after the close of a governing operation with the result that a higher speed will correspond to the new lighter load (positive returning). If the link 27 be arranged in the dotted line position 27^a, the point 9 will be lowered at every closing movement of the shaft 16, thus causing the sleeve of the spring governor to occupy a lower position after the governing operation. The speed will then be less than before for the new, lighter load (negative returning). In all these cases a method of governing practically free from oscillation or hunting is also obtained by means of apparatus forming the subject matter of the invention. A governing operation in general takes place in a perfectly similar manner to what has been hereinbefore described in reference to constant speed governing without returning mechanism, Fig. 8. The only difference consists in the fact that a greater or lesser displacement of the dash pot piston 18 in the dash pot cylinder 17 takes place during a governing operation, other conditions being equal. The amount of displacement will be less when the movement imparted to the rod 10 by the returning mechanism is in the opposite direction to that caused by the centrifugal governor, as is the case in "positive returning." The amount of the displacement will be greater when the movements of the returning mechanism and the centrifugal governor act in the same direction on the rod 10.

The course of a governing operation with positive and negative returning arrangements respectively is illustrated diagrammatically in Fig. 10, the full line curves applying to positive and the dash-and-dot curves to negative returning arrangements. In the case of the "positive returning" arrangement the speed n^{11} attained at the time t^{11} at the close of the governing operation is higher by a certain amount than the speed n^s before the lightening of the load. Conversely, in the "negative returning" arrangement the speed n^{12} during the subsequent period of dwell and which is attained at the time t^{12} is less by a certain amount than that obtaining before the reduction in load.

In all the cases hereinbefore described it is essential toward attaining freedom from oscillation or "hunting" in governing mechanism that the controlling piston 3 shall be

5 returned to its mid position by the dash pot 17 to 22 immediately after the change in the speed has been set up, and that this shall necessitate only a very small backward movement or reverse change in the speed 10 and only a very brief period of time, by which means it is rendered possible for the state of equilibrium (which always prevails at the time when the change in the speed takes place) between the amount of energy supplied to the prime mover and the amount of power furnished by the latter, to be maintained at least approximately constant until the close of the governing operations.

15 The returning spring 21 shown in Fig. 6 comes into action when the load on the turbine is increased, the spring 22 then remaining inoperative. The dash pot cylinder may 20 in some cases be filled with water, air or the like, instead of oil. As an alternative, the springs may be arranged externally to the dash pot cylinder and act on the piston rod instead of on the piston itself as has 25 been shown in Fig. 11. The springs 34 rest with their one end on the outside of the dash pot cylinder while the upper end of the upper spring is fixed to the rod of the controlling linkage system that is connected to 30 the dash pot piston and the lower end of the lower spring is fixed to the rod of the controlling linkage system that is connected to the controlling valve for the auxiliary 35 motor. The working of this dash pot is the same as the working described with reference to Fig. 6.

If desired some other device equivalent in action to a dash pot for instance a friction coupling, may be employed instead of 40 a dash pot such a friction coupling has been shown in Figs. 12 and 13. The rod 35 of the controlling linkage system, intercalated between the centrifugal governor and controlling valve, that is connected to the controlling 45 valve carries at its upper end a piston 36 guided by two guide shoes 37 and 38 within a cylinder casing 39. The two guide shoes are arranged opposite to each other in the same diameter and are pressed 50 by means of springs 40 and 41 toward the piston 36. The casing 39 is hanged up to the rod 42 of the controlling linkage system. The working of such a friction coupling is the same as the working of a dash 55 pot. Upon the centrifugal governor being caused to rotate at a higher speed owing to the load on the prime mover being lightened, the rod 42 presses the cylinder casing 39 downward.

60 The friction of the guide shoes 37 and 38 is so great, that in the short period of the movement, which is momentarily in a downward direction, it is not possible to overcome this friction and to admit of the 65 piston moving relatively to the two guide

shoes. A momentary driving connection is accordingly set up between the piston 36 and the controlling valve and consequently the piston 6 of the controlling valve will also be pressed downward till its sitting 70 upon the lower stop of the valve casing. From this moment by a further downward movement of the rod 42, the friction of the guide shoes will be overcome, this being possible by the yielding nature of the friction coupling. By an occurrent upward movement, the friction coupling will act as a rigid connection till the piston 6 has reached the upper stop of the casing.

75 Claims:

1. In a governing mechanism for prime movers the combination of a main governor shaft, an auxiliary motor acting upon said shaft, a controlling organ for said auxiliary motor traveling only within relatively narrow limits, a centrifugal governor, a controlling linkage system connecting said governor with said controlling organ, a yielding member in connection with said linkage system capable of continuing its travel after the controlling organ has reached its end positions, said yielding member being capable of imparting to the controlling organ, upon a reversing movement of the governor, the same degree of movement, substantially as described and for the purpose set forth.

80 2. In a governing mechanism for water-driven turbines the combination of a main governor shaft, a hydraulic auxiliary motor 100 acting upon said shaft, a controlling valve for said auxiliary motor traveling within relatively narrow limits, a centrifugal governor, a controlling linkage system connecting the centrifugal governor with the controlling valve, a yielding member in connection with said linkage system capable of continuing its travel after the controlling valve has reached its end positions, said yielding member being capable of imparting 105 to the controlling organ, upon a reversing movement of the governor, the same degree of movement, substantially as described and for the purpose set forth.

85 3. In a governing mechanism for prime movers the combination of a main governor shaft, an auxiliary motor acting upon said shaft, a controlling organ for said auxiliary motor traveling only within relatively narrow limits, a centrifugal governor, a controlling linkage system connecting said governor with said controlling organ, a dash pot in connection with the controlling linkage system and consisting of a cylinder and a perforated piston therein, substantially as described and for the purpose set forth.

90 4. In a governing mechanism for water-driven turbines the combination of a main governor shaft, a hydraulic auxiliary motor 130

6

acting upon said shaft, a controlling valve for said auxiliary motor traveling within relatively narrow limits, a centrifugal governor, a controlling linkage system connecting the centrifugal governor with the controlling valve, a dash pot in connection with the controlling linkage system and consisting of a cylinder and a perforated piston therein, substantially as described and for 10 the purpose set forth.

5. In a governing mechanism for water-driven turbines the combination of a main governor shaft, a hydraulic auxiliary motor comprising a casing and differential pistons 15 acting upon said shaft and a pipe system for fluid under pressure in connection with said casing, a controlling valve with stops intercalated in said pipe system, a centrifugal governor, a controlling linkage system 20 connecting the centrifugal governor with the controlling valve, a dash pot intercalated in the controlling linkage system and consisting of a cylinder and a perforated piston therein, substantially as described and for 25 the purpose set forth.

6. In a governing mechanism for prime movers the combination of a main governor shaft, an auxiliary motor acting upon said shaft, a controlling organ for said auxiliary 30 motor traveling only within relatively narrow limits, a centrifugal governor, a controlling linkage system connecting said governor with said controlling organ, a yielding member in connection with said linkage 35 system capable of continuing its travel after the controlling organ has reached its end positions, said yielding member being capable of imparting to the controlling organ, upon a reversing movement of the governor, the same degree of movement, springs 40 provided in connection with said yielding member acting to return it in its mid position after each displacement for restoring after each governing the given position of 45 the controlling organ in dependence upon the centrifugal governor, substantially as described and for the purpose set forth.

7. In a governing mechanism for water-driven turbines the combination of a main governor shaft, a hydraulic auxiliary motor 50 acting upon said shaft, a controlling valve for said auxiliary motor traveling within relatively narrow limits, a centrifugal governor, a controlling linkage system connecting the centrifugal governor with the controlling valve, a dash pot intercalated in the controlling linkage system and consisting of a cylinder and a perforated piston 55 therein, springs provided in connection with the dash pot and acting to return the dash pot cylinder after each displacement to its mid position for restoring after each governing the given position of the controlling valve in dependence upon the centrifugal governor, substantially as described and for 60 the purpose set forth.

8. In a governing mechanism for water-driven turbines the combination of a main governor shaft, a hydraulic auxiliary motor comprising a casing and differential pistons 70 acting upon said shaft and a pipe system for fluid under pressure in connection with said casing, a controlling valve with stops intercalated in said pipe system, a centrifugal governor, a controlling linkage system 75 connecting the centrifugal governor with the controlling valve, a dash pot intercalated in the controlling linkage system and consisting of a cylinder and a perforated piston therein, springs provided in connection 80 with the dash pot and acting to return the dash pot cylinder after each displacement to its mid position for restoring after each governing the given position of the controlling valve in dependence upon the 85 centrifugal governor, substantially as described and for the purpose set forth.

In testimony that I claim the foregoing as my invention, I have signed my name in presence of two subscribing witnesses.
